(57) CLAIM

The ornamental design for a golf shoe outsole, as shown and described.

DESCRIPTION

FIG. 1 is a bottom perspective view of a golf shoe outsole showing our new design;

FIG. 2 is a rear elevational view thereof;

FIG. 3 is a front elevational view thereof;

FIG. 4 is a bottom plan view thereof;

FIG. 5 is a left side elevational view thereof;

FIG. 6 is a top plan view thereof; and,

FIG. 7 is a right side elevational view thereof.

The broken line showing of the upper portion of the shoe is for illustrative purposes only and forms no part of the claimed design. The broken lines indicating cleat locations form no part of the claimed design.

1 Claim, 3 Drawing Sheets

FIG. 4

FIG. 5
